CLOSURE STRUCTURE

Joseph E. Morris, Pasadena, Calif.

Application November 30, 1935, Serial No. 52,412

3 Claims. (Cl. 20—52.1)

My present invention relates to closure structures, and primarily to structures in which the closures slide horizontally.

The objects of my invention are:

5 First, to provide a closure structure whereby a solid or transparent closure such as a window, is easily convertible into a ventilating means, such as a screen, or into an opaque panel;

10 Second, to provide such a structure in which a window and blind or screen, normally secured together edge to edge are readily separated so that the closure opening may be wholly opened any desired distance when desired;

15 Third, to provide a closure structure which is substantially weatherproof except through the ventilating closure members;

20 Fourth, to provide novel means of draining water to the outside of the building and further to prevent splashing of water on the walls of hidden recesses for enclosing the withdrawn closure members;

25 Fifth, to provide novel and simple means of securing the closure members in any shifted position;

Sixth, to provide a closure structure in which the means for locking the members together or in place may not be readily tampered with;

30 Seventh, to provide a closure structure in which a window may be interchangeably attached to a blind or screen and either of the latter drawn over the window opening when the window is withdrawn; and

35 Eighth, to provide as a whole a novel closure structure, which is simple and economical of construction, and which will not readily get out of order.

With these and other objects in view, I have devised a closure structure having certain novel features of construction, as will appear herein-40 after and particularly set forth in the appended claims, reference being had to the accompanying drawing and to the characters of reference thereon which form a part of this application, in which;

45 Fig. 1 is an elevational view taken from the inside of the room showing my closure structure in its preferred form, portions being broken away to facilitate the illustration;

50 Fig. 2 is a section thereof in plan taken through 2—2 of Fig. 1;

Figs. 3 and 4 are enlarged sections thereof taken respectively through 3—3 and 4—4 of Fig. 2;

55 Fig. 5 is a section similar to Fig. 2 showing the

window partly pushed to one side and a screen shifted in its place;

Fig. 6 is a fragmentary elevation thereof; and, Fig. 7 is a section similar to Figs. 2 and 5 of a slightly modified form of my invention.

In the embodiment of my invention, as shown in the drawing, I have shown a window frame 1 in a building wall 2, a window 3, closure 4, and enclosures 5 and 6 forming recesses for the reception of the window and closure. The closure here referred to may be a conventional shutter, a screen, or the like. In the drawing, I have shown both a screen 4^a and blind 4^b, side by side, the blind at the outer side, and both together substantially the thickness of the window sash. The window and other closure are each preferably of substantially the width of the window or frame opening 4^c, and they are positioned side by side and edge to edge, that is, with the vertical edges of the blind and screen abutting the same vertical edge of the window. The enclosures referred to are wall portions at the opposite sides of the frame which form the narrow recesses 5^a and 6^a for the reception of the whole of the window and other closure respectively.

It will be here noted that for the purpose of convenience, the screen 4^a and blind 4^b are herein referred to as a closure 4.

The window 3 and closure 4 are separate units which are detachably connected by a suitable lock, so that when the window is pushed to one side the closure 4 is drawn with it to cover the space left by the withdrawn window. The disconnection of the window 3 and closure 4 also permits each to be withdrawn into its respective recess so as to provide a clear opening of the window, either whole or part.

In Figs. 1, 2, 5, and 6 of the drawing I have shown the window sash as having two locks 11 and 12 which have separate bolts or latches separately secureable to the screen 4^a and blind 4^b, respectively, as desired, by the operation of the desired lock. The window sash is preferably secured to either the screen or blind when the window is drawn over the window opening. Fig. 5 shows the screen attached to the window.

To the edge of one of the closure members, preferably the window, is secured a metal strip 21, having flanges 21^a which extend toward the screen and blind, and over the outer sides thereof, and are adapted to cover the slits between the adjacent closures when secured together. These flanges 21^a are adapted to exclude water, dust, and the like from the room and are also intended

to prevent ready access to the interior of the room through the slits.

The lower edge portion of the window, screen and blind have a plurality of transverse holes, 5 the holes in the window being designated 3^a and those in the screen and blind 4^a. These holes are for the reception of the plungers or bolts of locking devices 31 and 32. These bolts are withdrawn to allow free shifting of the closure members. If desired, only one of such locking bolts 10 may be used.

On the sill 1^b of the window frame is a trough 41, as shown in Fig. 3, which trough extends across and beyond the width of the frame opening. The inner edge has an upwardly turned flange 41^a to prevent rain from coming into the room. The trough is provided intermediate its inner and outer edges with track sections 41^b and 41^c upon which the closure members may ride. 15 The ends of this trough extend into the recesses 5^a and 6^a for catching any rain entering the recesses or dripping from the closure members which may be wholly or partly pushed into the recesses. However, the portions of the trough 20 in the recesses have upwardly extending walls at their outer edges, these walls being designated 42. These splash plates are intended to prevent rain, or the like, from entering the crevices or from being deflected from the partially open closure 25 members onto the wooden or other wall and saturating the same or causing rot or dampness. The water from these splash boards or plates runs into the troughs below and into the trough portion at the bottom of the window opening and 30 then onto the sill.

The track sections 41^b extend the full length of the trough and support and guide the window 3 and screen 4^a, while the track sections 41^c may extend only through the recess 6^a and over the 35 sill 1^a and support and guide the blind 4^b.

In the modification, shown in Fig. 7, my invention is applied to a double sliding window, the windows being indicated 51 and 52. In this instance, the window 52 needs no recess, the same 40 being shifted only in front of the window 51.

Only the closure member, blind or screen 4 requires a recess or an enclosure.

Though I have shown and described a particular construction and modifications thereof, I do not wish to be limited to the same, but desire to 5 include in the scope of my invention the construction, combination and arrangement substantially as set forth in the appended claims.

I claim:

1. In a closure structure, a closure frame, a 10 pair of closure members positioned edge to edge, said closure members being shiftable with respect to the frame, one being shifted over the opening as the other is withdrawn, and a drain trough at the bottom of the space beyond the opposite 15 sides of the opening, the troughs discharging from the adjacent ends at the bottom of the opening, and splash plates extending upwardly from the forward sides of the troughs in said 20 spaces.

2. In a closure structure, a closure frame having deep recesses at the opposite sides, a pair of closure members positioned edge to edge and each substantially the width of the opening encompassed by the frame and adapted to cover the 25 opening when shifted thereover, said closure members being shiftable with respect to the frame in the direction of said width, one being shifted over the opening as the other is withdrawn, said closure members being also separable 30 and each being shiftable into a separate recess at the opposite side of the frame.

3. In a closure structure, a closure frame having in a window opening and recesses at the opposite sides of the opening, a window slidably in 35 the frame over the opening and slidably into one of the recesses, a separate blind and screen, one positioned in front of the other and both adapted to be wholly concealed in the other recess, the combined thickness of the blind and screen being 40 substantially that of the window, and means for separately attaching one edge of the blind or screen to the adjacent edge of the window.

JOSEPH E. MORRIS. 45
